UNITED STATES PATENT OFFICE.

CHARLES D. SEEBERGER, OF YONKERS, NEW YORK.

CONVEYER.

No. 917,902.

Specification of Letters Patent.

Patented April 13, 1909.

Application filed March 31, 1902, Serial No. 100,860. Renewed June 10, 1905. Serial No. 264,733.

To all whom it may concern:

Be it known that I, CHARLES D. SEEBERGER, a citizen of the United States, residing at Yonkers, in the county of Westchester and State of New York, have invented certain new and useful Improvements in Conveyers, of which the following is a specification.

My invention relates to certain new and useful improvements in conveyers, and is designed to produce a device of that class in which each step may be supported upon a truck or bearing having only two wheels or shoes instead of the four which have hitherto been employed in practice, thus reducing not only the number of wheels, but also the number of tracks employed, as the four wheel trucks require a double track instead of a single one.

In perfecting my invention, I have devised a novel system of parallel linkage by which the tread surfaces of the steps are kept horizontal, whether they are traveling on a horizontal track to form a landing or on an inclined track to form the ascending or descending steps, while at the same time permitting them to pass readily around the terminal curves or loops, and that without the necessity of slotting the links as has been done hitherto. The linkage is for compactness, preferably placed under the steps.

My invention is also concerned with a novel propelling mechanism for the trucks.

To illustrate my invention I annex hereto three sheets of drawings in which the same reference characters are used to designate identical parts in all the figures, of which—

Figure 1 is a diagrammatic view in side elevation of the steps and links, with all the other mechanism omitted, and intended to show the relative positions assumed by the steps and links in all positions throughout the circuit; Fig. 2 is a side elevation, partly in section and on an enlarged scale, showing the steps and links on a horizontal portion forming a landing; Fig. 3 is a similar view on an inclined portion; Fig. 4 is a rear elevation in section on the line A—A of Fig. 3, and with the risers removed; Fig. 5 is a plan view of the same with a portion of one of the treads broken away; Fig. 6 is a section showing how the steps are driven; and Fig. 7 is a plan view of the links immediately over the driving pinion with the steps to which they are connected removed.

In carrying out my invention, a single

track *a* is employed on the inner side of each track support *b*, the tracks and supports taking whatever design may be necessitated by the conditions under which the apparatus is to be operated, one design being indicated by 60 the dotted line *a* in Fig. 1.

Each step *c* consists of a tread surface *d*, a riser *e*, and the end pieces *f*, and may be constructed in any desired manner, and is provided with an axle bar or shaft *g*, which 65 has the wheels *h*, or some equivalent support, such as sliding shoes, etc., mounted on the ends thereof in the plane of the tracks *a*, so that as the steps are advanced, the wheels roll on the tracks in the customary manner. 70

Mounted in the ends *f* of each step is the step bar or rod *j*, which preferably extends entirely across the step a short distance directly above and parallel to the axle bar or rod *g*. Each step is connected with each of 75 the adjacent steps by one or more axle links *k*, which are pivoted on the axle bars *g*, at suitable points intermediate their ends and are preferably held from movement longitudinally of the axle bar or shaft by the collars 80 *l*, or by any other suitable mechanism. In order to permit the steps to pass around the curves at the ends of the circuit, as shown in Fig. 1, these axle links are substantially U-shaped so as to permit the noses, or risers, 85 as the case may be, of the steps to assume the necessary positions without interfering with the links. As shown in Figs. 4 and 7, the adjacent links are staggered or in different vertical planes to prevent interference with each other. Similarly mounted on the step bars or rods *j* at suitable points intermediate their ends are the step links *m*, which will be seen to have the enlarged, substantially semi-circular ends *n*, which are 95 necessary to provide for the semi-circular recesses or slots *o* formed therein concentric with the step bars *j* and through which the axle bars or shafts *g* pass so that the step links and axle links may swing freely as is 100 necessary in changing from the horizontal position shown in Fig. 2 to the inclined position shown in Fig. 3, and in passing around the curves or loops at the ends without interference. The recesses *o* are of the proper length to allow the necessary swinging movement of the steps relative to each other required to pass around the curves, but no more, as this limitation of the length assists in returning the steps to and retaining them in 110

their horizontal position. For the same purpose that the axle links k are made U-shaped, the step links m are likewise U-shaped, and they are likewise staggered on their step bars or rods to prevent interference. With the construction herein shown and devised, I have provided a parallel linkage system which serves to hold the tread surfaces of the steps firmly in a horizontal plane whether 5 they are traveling on a horizontal or an inclined track, and at the same time permits them to pass around the curved ends or loops without any interference or actual shortening of the links as has been necessitated by the system of parallel linkage heretofore employed. To drive these steps, I have devised the novel mechanism best shown in Figs. 6 and 7, where it will be seen that I provide a driving shaft p , which is connected with any convenient source of power, and which has thereon one or more driving gears or pinions q , which mesh with the rack teeth r which are preferably formed on the straight edged bottoms of both the step links 10 m and axle links k . As indicated in Fig. 1, this driving shaft and its pinion are preferably located in the inclined portion of the circuit as near to the top thereof as may be, and the links are so designed that when the 15 steps are in this position, the rack bars or teeth are overlapped, and form a practically continuous rack bar on both sides of the pinion, so that as the driving shaft is rotated, the ascending steps are positively driven upward while the descending steps are positively driven downward. The driving of the 20 steps by means of the pinions thus coöperating with the rack bars formed on the bottoms of the links assists to hold the steps rigidly in 25 the desired position with their tread surfaces horizontal.

While I have shown the various features of my invention as embodied in the form which I at present consider best adapted to 30 carry out its purposes, it will be understood that it is capable of modifications, and that I do not desire to be limited in the interpretation of the following claims except as may be necessitated by the state of the prior art.

50 What I claim as new, and desire to secure by Letters Patent of the United States is—

1. In a device of the class described, the combination with a pair of tracks consisting of horizontal and inclined portions and the 55 necessary curves to make a complete circuit, of a series of steps each provided with a pair of supports coöperating with said tracks, and a system of parallel links having a constant length connecting said steps so as to hold 60 their tread surfaces in a horizontal position on the horizontal and inclined portions of the track.

2. In a device of the class described, the combination with a pair of tracks consisting 65 of horizontal and inclined portions and the

necessary curves to make a complete circuit, of a series of steps each provided with a pair of supports coöperating with said tracks, a system of parallel links having a constant length connecting said steps so as to hold 70 their tread surfaces in a horizontal position on the horizontal and inclined portions of the track, and means for driving said steps.

3. In a device of the class described, the combination with a pair of tracks consisting 75 of horizontal and inclined portions and the necessary curves to make a complete circuit, of a series of steps each provided with a pair of supports coöperating with said tracks, a system of parallel links having a constant 80 length connecting said steps so as to hold their tread surfaces in a horizontal position on the horizontal and inclined portions of the track, and means for driving said steps consisting of a driving pinion meshing with rack 85 bars formed on the bottom of said links.

4. In a device of the class described, the combination with a pair of tracks consisting of horizontal and inclined portions and the necessary curves to make a complete circuit, 90 of a series of steps each provided with a pair of supports coöperating with said tracks, and a system of substantially U-shaped links connecting the central portions of said steps.

5. In a device of the class described, the 95 combination with a pair of tracks consisting of horizontal and inclined portions and the necessary curves to make a complete circuit, of a series of steps each provided with a pair of supports coöperating with the said tracks, 100 and a system of links connecting the central portions of said steps and located entirely beneath them.

6. In a device of the class described, the combination with the tracks, of the steps 105 having a single support at each end coöperating therewith, links of constant length connecting said steps and provided with rack teeth formed thereon, and a driving pinion 110 engaging the teeth of said links for the purpose described.

7. In a device of the class described, the combination with the tracks, of the steps coöperating therewith, the axle links and the step links connecting said steps and provided 115 with the rack bars thereon, and the driving pinion meshing with said rack bars.

8. In a device of the class described, the combination with the tracks, of the steps coöperating therewith, the axle links and the 120 step links connecting said steps, and driving means for engaging both the axle and the step links for propelling the steps.

9. In a device of the class described, the combination with a pair of tracks consisting 125 of horizontal and inclined portions and the necessary curves to make a complete circuit, of a series of steps each provided with a pair of supports coöperating with said tracks, an axle link connecting each adjacent pair of 130

said steps, a step link connecting each adjacent pair of said steps and pivoted to their respective steps between the axle link and the tread surface thereof.

5 10. In a device of the class described, the combination of the tracks, with the wheeled steps coöperating therewith, the axle bar having the wheels on the ends thereof in the plane of said tracks, the axle links connecting said axle bars, and the step links pivotally connected to the steps above the axle bars.

15 11. In a device of the class described, the combination of the tracks, with the wheeled steps coöperating therewith, the axle bar having the wheels on the ends thereof in the plane of the tracks, the step links connected to the steps above the axle bars and provided with the slots concentric with their pivotal point and through which the axle bars pass, 20 and axle links pivotally connecting the bars.

25 12. In a device of the class described, the combination with a pair of tracks consisting of horizontal and inclined portions and the necessary curves to make a complete circuit, of a series of steps each provided with a pair of wheels coöperating with said tracks, the axle bars having the wheels on the ends thereof, the axle links connecting said bars, and the step links pivotally connected to the steps above the axle bars and provided with the slots concentric with their pivotal point and through which the axle bars pass.

35 13. In a device of the class described, the combination with a pair of tracks consisting of horizontal and inclined portions and the necessary curves to make a complete circuit, of a series of steps each provided with a pair of wheels coöperating with said tracks, the axle bars having said wheels on the ends thereof, the axle links connecting said axle bars, the step bars secured to said steps above the axle bars, and the step links pivotally connected to the step bars and provided with the slots therein concentric with the step bars and 40 through which the axle bars pass.

45 14. In a device of the class described, the combination with a pair of tracks consisting of horizontal and inclined portions and the necessary curves to make a complete circuit, of a series of steps each provided with a pair of wheels coöperating with said tracks, the axle bars having said wheels on the ends thereof, the substantially U-shaped axle links connecting said bars near the center thereof, the step bars located above the axle bars, and the substantially U-shaped step links pivotally connected to the axle bars near their center and provided with the slots concentric with said step bars and through 50 which the axle bars pass.

55 15. In a device of the class described, the combination with a pair of tracks consisting of horizontal and inclined portions and the necessary curves to make a complete circuit, of a series of steps each provided with a pair

of wheels coöperating with said tracks, the axle bars having said wheels on the ends thereof, the substantially U-shaped axle links connecting said bars near the center thereof, the step bars located above the axle bars, the substantially U-shaped step links pivotally connected to the axle bars near their center and provided with the slots concentric with said step bars and through which the axle bars pass, the rack teeth formed on the bottoms of said U-shaped links, and the driving pinion meshing with said links.

70 16. In a device of the class described, the combination with the tracks consisting of horizontal and inclined portions and the necessary curves to make a complete circuit, the ascending and descending inclined portions being parallel to each other, of the steps coöperating with said tracks, links connecting said steps and provided with rack teeth formed thereon, and the driving pinion centrally located between the ascending and descending portions near the upper end of the inclined portion thereof in position to engage with the rack teeth of both the ascending and descending steps.

75 17. In a device of the class described, the combination with the tracks, of a series of steps provided with supports coöperating with said tracks, and a system of parallel links of constant length connecting said steps in different planes.

80 18. In a device of the class described, the combination with the tracks, of a series of steps provided with supports coöperating with said tracks, and a system of parallel links of constant length connecting said steps and located beneath them, and a driving pinion engaging the links.

85 19. In a device of the class described, the combination with the tracks, of a series of steps provided with supports coöperating with said tracks, and a system of substantially U-shaped parallel links of constant length connecting said steps.

90 20. In a device of the class described, the combination with tracks, of the steps moving thereon, parallel links connecting said steps, and driving mechanism engaging said links and tending to advance the steps and hold their tread surfaces horizontal.

95 21. In a device of the class described, the combination with the steps or carriages and the tracks therefor, of parallel linkage connecting said steps to maintain them in predetermined relation to each other upon the landing as well as upon the incline.

100 22. In a device of the class described, the combination with the steps or carriages and tracks therefor, of parallel linkage of constant length connecting said steps to maintain their treads horizontal.

105 23. In a device of the class described, the combination with the steps or carriages and tracks therefor, of parallel links connecting

said steps to maintain the steps in horizontal position on both the inclined and horizontal runs.

24. In a device of the class described, the combination with a pair of tracks consisting of horizontal and inclined portions and the necessary curves to make a complete circuit, of a series of steps arranged to travel on said tracks, two sets of links of constant length connecting the steps to hold their treads horizontal, and means engaging the links for driving the steps.

25. The combination in an inclined moving stairway, of a single track at each side 15 of the stairway, step sections each having a single wheel at each end arranged to travel on the said tracks, two sets of links of constant length connecting and retaining the step sections in a horizontal position, and 20 means engaging the links for driving said step sections.

26. The combination in a moving stairway, of inclined and horizontal tracks, step sections arranged to travel on said tracks, 25 rods on each step section, two sets of links of constant length connecting the rods, and means for driving the said sections.

27. The combination in a moving stairway, of inclined and horizontal tracks, step- 30 sections having a single wheel at each end to travel over both tracks and arranged in step form on the inclined portion and flat on the horizontal portion, links of constant length connecting the sections together, said 35 sections being free to pivot on the links.

28. The combination in a moving stairway, of inclined and horizontal tracks, step sections each having a single wheel at each end arranged to travel on the tracks, an 40 axle-bar and rod on each step section, and links of constant length connecting the bars and rods of the several steps.

29. The combination in a moving stairway, of tracks, step sections having a single 45 wheel at each end to travel on said tracks, links of constant length connecting the step

sections forming an endless chain, the links having teeth arranged to be engaged by the driving means.

30. The combination in a moving stair- 50 way, of tracks, step sections having a single wheel at each end to travel on said tracks, links of constant length connecting the step sections and forming an endless chain, the links having gear teeth, and a gear arranged 55 to engage the toothed links and so arranged that it will always be in mesh with the endless chain.

31. The combination in a moving stair- 60 way, of tracks, step sections arranged to travel on said tracks, two sets of links connecting the steps, the links being curved to clear the riser of the step section.

32. The combination in a moving stair- 65 way, of a plurality of steps forming an endless system, two substantially parallel series of toothed links connected to the steps, with a driving gear mounted to simultaneously engage the toothed links of both series.

33. The combination in a moving stair- 70 way, of a series of steps forming an endless system, two series of toothed links connected to the steps and forming substantially continuous racks, and a toothed gear constructed to simultaneously engage the 75 toothed links of both series on the ascending and descending runs.

34. A moving stairway consisting of a series of step sections forming an endless system, two series of toothed links carried 80 by the step sections so as to form a continuous rack and arranged with their toothed faces in the same planes, and two driving gears engaging said toothed links at the ascending and descending runs of the stair- 85 way.

In testimony whereof I affix my signature in presence of two witnesses.
